DESIGN FOR A FLOWER BASKET

Edward A. Bittel, Rochester, N. Y., assignor to George B. Hart, Inc., Rochester, N. Y., a corporation of New York

Application June 24, 1938, Serial No. 78,027

Term of patent 3½ years

To all whom it may concern:

Be it known that I, Edward A. Bittel, a citizen of the United States, residing at Rochester, in the county of Monroe and State of New York, have invented a new, original, and ornamental Design for Flower Baskets, of which the following is a specification, reference being had to the accompanying drawing, forming part thereof:

In the drawing:

I claim:

The ornamental design for a flower basket, as shown.

EDWARD A. BITTEL.
